THOMAS LINCOLN AND GEORGE HUBBARD, OF NEW HAVEN, CONNECTICUT.

Letters Patent No. 88,186, dated March 23, 1869.

IMPROVEMENT IN DOOR-BUTTONS.

The Schedule referred to in these Letters Patent and making part of the same.

To all whom it may concern:

Be it known that we, THOMAS LINCOLN and GEORGE HUBBARD, of New Haven, in the county of New Haven, and State of Connecticut, have invented a new Improvement in Door-Button; and we do hereby declare the following, when taken in connection with the accompanying drawings, and the letters of reference marked thereon, to be a full, clear, and exact description of the same, and which said drawings constitute part of this specification, and represent, in—

Figure 1, a top view;

Figure 2, the same, with the button turned;

Figure 3, an under-side view of the turn-button;

Figure 4, a top view of the plate, with the button removed; and in

Figure 5, a sectional view, between the plate and button, looking toward the button.

This invention relates to an improvement in the article of manufacture known to the trade as door, or turn-buttons, the object being to provide the button with a mechanism which shall automatically turn the button to right angles, or nearly so, when the button has been partially turned toward such angle; and

The invention consists in forming, upon the plate, a square boss, and a recess, within the button, setting over the said square boss, and with springs fitted into the recess in the button, and bearing upon the said boss, so that the natural place of rest is upon one of the sides of the boss, and so that when the button is turned to carry the spring over one of the angles, the reaction of the spring will force the button over, so as to carry the spring on to the flat surface of the boss.

To enable others to fully understand our invention, we will describe the same, as illustrated in the accompanying drawings.

A is the plate, formed with a square boss, *a*, or with a projection, having one or more flat surfaces, *B*.

The turn-button is provided with a recess, *C*, on its under side, so as to set on over the boss; and through a central perforation in the button, and through the boss, a rivet, *d*, is placed, to secure the two parts together, and form a pivot, upon which the button turns.

The recess in the button is sufficiently broad to permit the button to turn freely around the boss *a*; and in the said recess, upon one or both sides, we place a spring, *f*, (see fig. 5,) the tendency of which is to retain the button with the springs lying upon the flat side of the boss. Therefore, when the button is partially turned, so as to remove the springs from the flat surface, the said springs will, of their own inclination, carry the button around, so that the springs will rest upon the nearest flat surface, whether it be in the position seen in fig. 1 or fig. 2.

We do not wish to be understood as broadly claiming the construction of a turn-button, so that it will be held in any given position, as such, we are aware, is not new; but

What we do claim as new and useful, and desire to secure by Letters Patent, is—

The button *B*, provided with the recess *C*, and combined with the plate *A*, constructed with the boss *a*, and fitted with one or more springs, *f*, so as to operate substantially in the manner specified.

THOMAS LINCOLN.
GEORGE HUBBARD.
